FIG. 1

1

2,881,561

POWER AND STEERING UNIT

Douglas D. Raze, Minneapolis, Minn.

Application January 14, 1957, Serial No. 633,974

9 Claims. (Cl. 46—211)

This invention relates to power and steering units. More particularly it relates to a self-contained power and steering unit capable of automatically changing the direction of its movement when an obstruction is encountered.

Various units have been constructed in the past for the purpose of providing a mechanism which will automatically change its direction of movement when an obstruction is encountered so as to enable the device to continue across a planar surface. Such a device is especially desirable for use in the construction of children's toys. My own two prior patents, Patent No. 2,641,869 issued to me June 16, 1953 and entitled, Toy Steering Mechanism and Patent No. 2,171,294 issued to me August 29, 1939 and entitled, Power and Steering Mechanism, are examples of such devices. Most such units, however, are relatively complex in structure and are so expensive to manufacture and market as to make the sales thereof in large volume not feasible. My instant invention is directed toward overcoming these disadvantages.

It is a general object in my invention to provide a novel and improved power and steering unit of inexpensive and simple construction and operation.

A more specific object is to provide a novel and improved power and steering unit requiring a minimum of parts, being inexpensive in structure and cost of assembly, and functioning in an improved manner and upon a different principal.

Another object is to provide a novel and improved power and steering unit which will repeatedly change directions when engaging an obstruction until the obstruction has been cleared by the unit.

Another object is to provide a novel power and steering unit constructed so simply and inexpensively as to lend itself readily to large scale production at a minimum of cost.

Another object is to provide a novel and improved power and steering unit which utilizes a guide member in cooperation with a single propelling element to determine the normal direction of movement of the unit and to alter the same when an obstruction is encountered by the unit.

Another object is to provide a novel and improved power and steering unit which utilizes the tilt of a tiltably mounted frame to determine and alter the direction of movement of the unit itself.

These and other objects and advantages of my invention will more fully appear from the following description made in connection with the accompanying drawings wherein like reference characters refer to similar parts throughout the several views and in which:

Fig. 1 is a bottom plan view of one embodiment of my invention; and

2

Fig. 2 is a vertical sectional view taken along line 2—2 of Fig. 1.

One embodiment of my invention as shown in Figs. 1—2 may include an inverted U-shaped metal frame 5 having a pair of depending legs 6 and 7. A spring motor 8 is mounted on the underside of the inverted frame 5 and has a drive shaft 9 extending upwardly and downwardly therefrom. This drive shaft 9 is driven by the spring motor 8 and carries a ring gear 10 secured to its lower portions. A spring latch member 11 having latching arms 12 and 13 is fixedly mounted on the lower end portion of the drive shaft 9. The resilient latching arms 12 and 13 serve to engage the ring gear 10 by means of openings 10a, 10b, 10c, 10d, 10e and 10f formed in the ring gear 10 for that purpose as best shown in Fig. 1. It will be readily seen that in this manner the spring motor 8 drives the ring gear 10 and the spring motor may be wound relative to the ring gear 10 through rotation of the drive shaft 9 in the direction indicated in the arrows of Fig. 1.

Carried by the lower end portion of the drive shaft 9 immediately below the latch member 11 is a mounting bracket 14. This mounting bracket 14 is secured to the lower end of the drive shaft 9 by a cotter key 15. A shaft 16 extending transversely of the frame is rotatably mounted in the mounting bracket 14 and extends outwardly therefrom in opposite directions. The shaft is journaled for rotation in the opposite legs 6 and 7 of the frame 5, the shaft extending outwardly beyond each of these legs and carrying a freely rotatable support wheel 17 at one of its ends and a drive wheel 18 at its other end portion. The wheels 17 and 18 hold the frame 5 and the shaft 16 in elevated relation to any planar surface such as the surface 19 upon which the wheels 17 and 18 may rest. The drive wheel 18 is fixed to the shaft 16 for rotation therewith while the support wheel 17 is mounted for free rotation relative to the shaft 16 and is in nondriving relation to the frame.

The shaft 16 is driven by means of a pinion 20 which is fixedly secured to the shaft 16 for rotation therewith and which cooperates with and is engaged by the ring gear 10. The pinion 20, the shaft 16 and the drive wheel 18 are all in driven relation to the ring gear 10 and the source of rotary power, the spring motor 8.

A gear train indicated generally as T is utilized for the sole purpose of preventing the spring motor 8 from unwinding too rapidly. This gear train T includes a countershaft 21 which is journaled in the forward portions of the depending legs 6 and 7 of the frame 5 and which carries a pinion 22 fixedly secured thereto. This pinion 22 cooperates with a gear 23 which is mounted on the shaft 16 in fixed relation with the pinion 20 so that as the pinion 20 rotates the gear 23 will rotate therewith and drive the pinion 22. Mounted on the opposite end of the countershaft 21 is another gear 24 which cooperates with a pinion 25 mounted for free rotation on the shaft 16 and fixedly secured to a gear 26 which in turn engages a pinion 27 carried by the counter shaft 21. A flywheel 28 is fixedly secured to the pinion 27.

Mounted on the forward portions of the depending legs 6 and 7 of the frame 5 is a guide wheel 30 which is mounted for free rotation relative to the frame on an axis extending parallel to the axis of the shaft 16. This guide wheel 30 has a soft rubber outer coating 31 which frictionally engages the planar surface 19 during the normal movement of the unit.

Mounted in encasing relation to the frame 5 and the rest of the unit previously described is a dome shaped

housing 32 which is open at the bottom and extends downwardly normally to within a short distance of the planar surface 19. As best shown in Fig. 2 this housing 32 is carried by the frame 5 via the drive shaft 9 which extends through an opening in the top of the housing. The housing 32 is normally maintained in spaced and elevated relation relative to the frame 5 and the wheels 17 and 18 by a coiled spring 33 which is disposed around the drive shaft 9 between the frame 5 and the under surface of the housing. A winding disc 34 is threaded unto the upper end of the drive shaft 9.

My power and steering unit is very simple to use. The spring motor 8 can readily be wound by pressing downwardly upon the housing 32 whereupon it will move to the broken line position shown in Fig. 2 so that the wheels 17 and 18 and the guide wheel 31 will be engaged thereupon and the lower edge of the housing 30 will engage the planar surface 19. By merely winding the winder disc 34 the power motor can then very easily be wound to tensioned position. During the course of the winding the spring lever 12 will slip from one of the openings 10a to 10b and thence to 10c successively and will serve to prevent the power motor from unwinding until the power and steering unit is released. Upon its release the power motor 8 will tend to unwind and will cause the latching arms 12 and 13 to drive the ring gear 10 which in turn will drive the pinion 20 and the drive-wheel 18 via the shaft 16. Since only the guide wheel 18 tends to propel the unit, the unit has a natural tendency to rotate about the non-driven support wheel 17 and would do so were it not for the guide wheel 30 which engages the planar surface 19 frictionally to preclude swinging and lateral movement thereof. As a result the unit will move forwardly in a straight line normal to the longitudinal axis of the shaft 16 until such time as an obstruction is encountered. When an obstruction is encountered by the unit (which may be the result of the housing 32 striking a foreign object such as a table, etc.) the ring gear 10 tends to climb around the pinion 20 in a reversed direction toward the rear of the frame so that the front end portions of the depending arms 6 and 7 and the guide wheel 30 will be slightly elevated or at least the weight of the unit will be taken off of the guide wheel 30 sufficiently to enable it to swing laterally. It will be seen that the frame is so constructed that the balance of weight of the unit is to the same side of the shaft 16 as the guide wheel 30 so that normally sufficient weight will be brought to bear upon the guide wheel to preclude lateral swinging. When an obstruction is encountered, however, a retarding action is placed upon the pinion 20 through the inability of the guide wheel 18 to move forwardly farther and hence the power motor 8 causes the ring gear to climb around the pinion 20 thereby elevating the guide wheel 31 slightly and taking the weight of the unit off the same. When this takes place, the guide wheel 30 will swing in the direction of the arrow adjacent thereto as shown in Fig. 1 and will continue to swing in that direction until the weight of the unit is again returned upon the guide wheel whereupon the unit will proceed forwardly in a direction normal to the axis of the guide wheel. It is obvious that as long as the obstruction is encountered the drive wheel 18 will continue to swing the unit about the non-driven wheel 17 and that when the obstruction is cleared the unit will again proceed in a straight line directional movement.

Thus it can be seen that I have provided an extremely simple and inexpensive device which is self-contained to power itself across a planar surface and to automatically vary its direction repeatedly until obstructions encountered thereby have been cleared. Such a device when utilized to power and steer a toy will propel the toy constantly so long as the power motor is wound up. This eliminates one of the chief criticisms of many toys which is that they become immovable when any obstruction

such as a wall, table or chair leg is encountered. Such toys soon lose their interest for children, especially those of younger years. A toy powered with my power and steering unit, however, will continue to move and amuse the child so long as it is wound up.

My power and steering unit has the advantage of being very simple and inexpensive to construct so that it can be manufactured and sold at a reasonable price thereby enabling people of moderate or less means to purchase the same as a toy for their children. It will be noted that it has a minimum of parts and that it is so simple in design that very little expense in the way of replacement of parts will ever be necessary.

It will, of course, be understood that various changes may be made in the form, details, arrangement and proportions of the parts without departing from the scope of my invention which consists of the manner shown and described herein and set forth in the appended claims.

What I claim is:

1. A power and steering unit comprising a frame, a source of rotary power carried by said frame, a pair of rotary support members rotatably mounted on said frame at opposite sides thereof for rotation about substantially parallel axes and adapted to engage a plane surface to support said frame thereabove, one of said rotary support members being at all times connected in driven relation to said source of rotary power for rotation in a single direction about its axis and the other being freely rotatable relative thereto, and a non-powered guide member carried by said frame at a point lateral of the axis of said driven rotary support member and normally frictionally engaging the plane surface supporting said support members to guide the direction of movement of the entire unit, said source of rotary power being constructed and arranged relative to said frame and said guide member to cause the latter to be elevated out of engagement with the plane supporting said support members when an obstruction is encountered by said unit to thereby cause said driven member to change the direction of said unit until the obstruction has been cleared.

2. A power and steering unit comprising a frame, a source of rotary power mounted on said frame, a pair of laterally spaced wheel members rotatably mounted on said frame for rotation about substantially parallel axes and adapted to engage a plane surface to support said frame thereabove, one of said wheel members being connected in driven relation with said source of rotary power for rotation in a single direction about its axis and the other being free to rotate relative thereto, and a non-powered guide wheel rotatably mounted on said frame at a point lateral of the axis of rotation of said driven wheel member for free rotation about an axis parallel to the axis of rotation of said driven wheel member and normally frictionally engaging the plane surface supporting said wheels to guide the direction of movement of the entire unit, said source of rotary power being constructed and arranged relative to said frame and said guide wheel to cause the latter to be elevated out of engagement with the plane supporting said wheels when an obstruction is encountered by said unit to thereby cause said driven wheel to change the direction of said unit until the obstruction has been cleared.

3. A power and steering unit having in combination a frame, a substantially horizontal shaft mounted on said frame, a source of rotative power mounted on said frame, a plurality of rotary support members mounted on said shaft and adapted to engage a plane surface and supporting said shaft and said frame thereabove, one of said rotary support members being connected with said source of rotative power in driven relation for rotation in a single direction about its axis and the other being free to rotate relative thereto; and a guide wheel freely rotatable about an axis substantially parallel to the longitudinal axis of said shaft and carried by said frame laterally of the longitudinal axis of said shaft and engaging the sur-

face transversed by said rotary support members in order to normally guide the movement of the entire unit, said source of rotative power being constructed and arranged relative to said frame and said guide wheel to cause the latter to be elevated out of engagement with the plane supporting said wheel and said support members when an obstruction is encountered by said unit to thereby cause said driven member to change the direction of said unit until the obstruction has been cleared.

4. A power and steering unit having in combination a frame, a substantially horizontal shaft mounted on said frame, a source of rotary power mounted on said frame, a plurality of rotatable support members mounted on said shaft at opposite end portions thereof and adapted to engage a plane surface to support said shaft and said frame thereabove, the rotary support member at only one end portion of said shaft being connected with said source of rotary power in driven relation for rotation in a single direction about its axis and the other being free to rotate relative thereto, and a non-powered guide member carried by said frame at a point lateral of the longitudinal axis of said shaft and normally engaging the plane surface supporting said support member to guide the direction of movement of the entire unit, said source of rotary power being constructed and arranged relative to said frame and said guide member to cause the latter to be elevated out of engagement with the plane supporting said support members when an obstruction is encountered by said unit to thereby cause said driven member to change the direction of said unit until the obstruction has been cleared.

5. A power and steering unit comprising, a frame, a shaft mounted for rotation about its longitudinal axis on said frame, a source of rotary power connected to said shaft in driving relation for rotation thereof in a single direction about its axis and being carried by said frame, a pair of wheel members mounted on said shaft and adapted to engage a plane surface to support said shaft and said frame thereabove, one of said wheel members being driven by said shaft in a single direction about its axis and the other being freely rotatable thereon, and a guide member carried by said frame and normally frictionally engaging the surface traversed by said wheel members at a point laterally of their axis of rotation to guide the movement of the entire unit, said frame being capable of substantial rotation about said shaft, said source of rotary power being constructed and arranged relative to said frame and said guide member to cause said guide member to be swung upwardly out of engaging relation to such surface by said frame and said source of power when an obstruction is encountered by the unit whereupon said driven wheel member will pivot around said freely rotatable wheel until the obstruction has been cleared and the unit is free to move in a new direction.

6. A power and steering unit comprising a frame, a shaft mounted for rotation about its longitudinal axis on said frame, a source of rotary power carried by said frame, a plurality of rotary support members mounted on said shaft and adapted to engage a plane surface to support said shaft and said frame thereabove, one of said rotary support members being connected at all times through said shaft in driven relation to said source of rotary power, for rotation in a single direction about its axis and the other being freely rotatable relative thereto and a guide wheel mounted on said frame laterally of the longitudinal axis of said shaft for free rotation about an axis substantially parallel to said shaft and normally engaging the plane surface engaged by said support members and guiding the directional movement of the entire unit, said frame being rotatable about said shaft, said source of rotary power being constructed and arranged and operatively connected relative to said shaft and said frame to cause said guide wheel to be elevated by said frame out of engagement with the plane surface

when an obstruction is encountered by the unit whereby the direction of movement of the unit will be changed by said driven rotary support member.

7. A power and steering unit comprising a frame, a substantially horizontal shaft mounted for rotation about its longitudinal axis on said frame, a source of rotary power mounted on said frame and connected to said shaft in driving relation for rotation of the same in a single direction about its longitudinal axis, a plurality of rotary support members mounted on said shaft and adapted to normally engage a plane surface to support said shaft and said frame thereabove, only one of said rotary members being connected to said shaft in driven relation, and a guide member carried by said frame and frictionally engaging the plane surface upon which said rotary support members normally rest at a point laterally of their axis of rotation, said frame being rotatable about said shaft to permit said guide member to be elevated by said frame out of engagement with the plane surface normally engaged thereby, the balance of weight of the entire unit being disposed laterally of the longitudinal axis of said shaft and said guide member being disposed laterally of said shaft on the same side thereof as that to which the balance of weight of the unit is disposed whereby said guide member will normally frictionally engage such a plane surface and may move to nonengaging position when an obstruction is encountered by the unit to cause said driven rotary support member to change the direction of movement of the entire unit, said source of rotary power being operatively connected and constructed and arranged relative to said shaft and said frame to cause said frame to tilt and thereby elevate said guide member to non-engaging position when an obstruction is encountered by said unit.

8. A power and steering unit comprising a frame, a source of rotary power mounted on said frame, a substantially horizontal axle mounted on said frame for rotation about its longitudinal axis and extending transversely thereof, a pair of spaced wheels mounted on said axle adapted to engage a planar surface and supporting said axle and said frame thereabove, gear mechanism connecting one of said wheels in driven relation with said source of rotary power for rotation in a single direction about its axis and the other of said wheels being freely rotatable and uncontrolled by said source of power, a guide member mounted on said frame and normally frictionally engaging the planar surface upon which said wheels rest at a point disposed laterally of said axle and operably connected with said source of rotary power to cause said frame to rotate, said frame being rotatable about said axle in a direction to lift said guide member out of engagement with the plane surface normally engaged thereby when an obstruction is encountered by the unit to cause said driven wheel to change the direction of movement of the entire unit.

9. A power and steering unit comprising an inverted U-shaped frame having depending legs thereon, a shaft mounted for rotation about its longitudinal axis on said legs and extending substantially horizontally therebetween, a source of rotary power mounted on said frame and driveably connected with said shaft to rotate the same in a single direction about its longitudinal axis, a plurality of rotatable support members mounted on said shaft and adapted to engage a plane surface and support the same and said frame thereabove, only one of said support members being drivably connected with said shaft and the other being free to rotate relative thereto, a guide member mounted on said frame and normally frictionally engaging the plane surface engaged by said rotary support members at a point disposed laterally of said shaft and determining in cooperation with said driven support member, the direction of movement of the unit, said frame being rotatable about the longitudinal axis of said shaft, the balance of weight of the entire unit being disposed laterally of said shaft and said guide member

also being disposed laterally of said shaft in the same direction as the balance of weight of the unit, said source of rotary power being operably connected to and constructed and arranged relative to said frame to cause said frame to tilt and lift said guide member out of engagement with its supporting plane surface when an obstruction is encountered by the unit whereupon said driven support member will change the direction of the unit.
